(57) **CLAIM**

The ornamental design for a decoration assembly, as shown and described.

DESCRIPTION

FIG. 1 is a front right perspective view of a decoration assembly embodying my new design, according to one embodiment;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof.

FIG. 8 is a front right perspective view of the decoration assembly embodying my new design, according to another embodiment;

FIG. 9 is a front view thereof;

FIG. 10 is a rear view thereof;

FIG. 11 is a left side view thereof;

FIG. 12 is a right side view thereof;

FIG. 13 is a top view thereof; and

FIG. 14 is a bottom view thereof.

FIG. 15 is a front right perspective view of the decoration assembly embodying my new design, according to another embodiment;

FIG. 16 is a front view thereof;

FIG. 17 is a rear view thereof;

FIG. 18 is a left side view thereof;

FIG. 19 is a right side view thereof;

FIG. 20 is a top view thereof; and

FIG. 21 is a bottom view thereof.

FIG. 22 is a front view of the decoration assembly embodying my new design, according to another embodiment;
 FIG. 23 is a rear view thereof;
 FIG. 24 is a left side view thereof;
 FIG. 25 is a right side view thereof;
 FIG. 26 is a top view thereof; and
 FIG. 27 is a bottom view thereof.
 FIG. 28 is a front view of the decoration assembly embodying my new design, according to another embodiment;
 FIG. 29 is a rear view thereof;
 FIG. 30 is a left side view thereof;
 FIG. 31 is a right side view thereof;
 FIG. 32 is a top view thereof; and
 FIG. 33 is a bottom view thereof; and,
 FIG. 34 is a front right perspective view of the decoration assembly embodying my new design, according to an embodiment in which the decoration assembly can be at least partially disassembled.
 Broken lines are used to illustrate portions of the decoration assembly that form no part of the claimed design. The appearance of any portion of the article between the break lines forms no part of the claimed design.
 The decoration assembly can be a party decoration (e.g., for birthdays, holidays, special occasions), and for example can be placed on or inserted into cakes and gifts (e.g., flower pots).
